UNITED STATES PATENT OFFICE

116,060

DESIGN FOR A PLATE OR SIMILAR ARTICLE

Victor Skellern, Fenton, Stoke-on-Trent, England, assignor to Josiah Wedgwood & Sons, Inc. of America, New York, N. Y., a corporation of New York

Application June 22, 1939, Serial No. 85,634

Term of patent 7 years

To all whom it may concern:

Be it known that I, Victor Skellern, a citizen of Great Britain, residing at 14 Maud Street, Fenton, Stoke-on-Trent, England, have invented a new, original, and ornamental Design for a Plate or Similar Article, of which the following is a specification, reference being had to the accompanying drawing, forming part thereof.

The drawing represents a plan view of a plate showing my new design, it being understood that the border decoration as shown in the drawing is continued around the border of the article.

I claim:

The ornamental design for a plate or similar article, as shown and described.

VICTOR SKELLERN.
